CLAIM

The ornamental design for a wine holder, as shown and described.

DESCRIPTION

FIG. 1 is a perspective view of a wine holder showing my new design;

FIG. 2 is a front side elevation view thereof;

FIG. 3 is a right side elevation view thereof;

FIG. 4 is a top plan view thereof; and,

FIG. 5 is a bottom plan view thereof.

The back side elevation view is a mirror image of FIG. 2. The left side elevation view is a mirror image of FIG. 3.
